UNITED STATES PATENT OFFICE

GEORGE H. PULSIFER, OF HAVERHILL, MASSACHUSETTS

DESIGN FOR A SHOE BUCKLE

Application filed February 13, 1930. Serial No. 34,525. Term of patent 3½ years.

To all whom it may concern:

Be it known that I, GEORGE H. PULSIFER, a citizen of the United States of America, residing at Haverhill, county of Essex, State of Massachusetts, have invented a new, original, and ornamental Design for Shoe Buckle, of which the following is a specification, reference being had to the accompanying drawing forming a part thereof.

Fig. 1 is a top plan view, and Fig. 2 is a side elevation of a shoe buckle, showing my new design.

I claim:

The ornamental design for a shoe buckle, substantially as shown.

GEORGE H. PULSIFER.
